(57) **CLAIM**

The ornamental design for an arm sleeve for training, as shown and described.

DESCRIPTION

FIG. 1 is a perspective view of an arm sleeve for training showing our new design;

FIG. 2 is a front side view thereof;

FIG. 3 is a rear side view thereof;

FIG. 4 is a bottom view thereof;

FIG. 5 is a top view thereof;

FIG. 6 is a left end view thereof;

FIG. 7 is a right end view thereof; and,

FIG. 8 is a perspective view thereof in an exemplary state of use.

In FIGS. 1-7, the arm sleeve for training is in a flat position. In FIG. 8 showing an exemplary state of use, the arm sleeve for training is worn while in a non-flat position, with a person's arm passing through the arm sleeve for training. In FIGS. 1 and 2, the dash-dash broken lines are directed to portions of the arm sleeve for training that form no part of the claimed design. The dash-dash broken lines represent bounds of the claimed design and do not themselves form a part of the claimed design. In FIG. 8, the dash-dot broken lines are directed to environment that forms no part of the claimed design.
